SIGNALING DEVICE

Joseph C. McCune, Edgewood, Pa., assignor to
The Westinghouse Air Brake Company, Wil-
merding, Pa., a corporation of Pennsylvania

Application January 28, 1937, Serial No. 122,701

30 Claims. (Cl. 116—24)

This invention relates to signaling devices and more particularly to means for controlling the operation of the signal device employed on locomotives.

There are a number of different whistle signals employed in railway service and the most frequently used signal consists of two long blasts followed by two short blasts which is employed at the approach to railway crossings. In the operation of high speed trains, such as are at present being employed in service, these crossings are often passed at short time intervals and the operation of the whistle at each of these crossings requires considerable time and attention by the engineer. In fact, such frequent operation of the whistle is liable to become such a burden to the engineer that he may at some time fail to operate the signal at the approach to a crossing and such failure may result in the wreckage of the train or damage to other properties and perhaps may result in the loss of life.

One object of the invention is to provide improved means adapted to operate automatically to effect the operation of a locomotive signal device to produce the desired signal at railway crossings or the like.

Another object of the invention is to provide improved means of the above type adapted, if desired, to be under the control of the engineer on whose part, a simple act, such as the mere depressing of a button, will initiate the operation of the means which will then continue to operate automatically to effect the operation of the signal means on the locomotive to produce the desired series of signal blasts.

Another object of the invention is to provide improved means of the above type the automatic operation of which is controlled wholly by fluid under pressure.

Other objects and advantages will be apparent from the following more detailed description of the invention.

In the accompanying drawing the single figure is a diagrammatic view of a signaling mechanism embodying the invention.

As shown in the drawing, the signaling mechanism comprises a signal producing device in the form of a fluid pressure operated whistle 1, a valve device 2 for controlling the supply of fluid under pressure from any suitable source of fluid under pressure, such as in a fluid pressure supply pipe 3, to said whistle for effecting the operation thereof, an operating device 4 for controlling the operation of the valve device 2, and a control

device 5 provided for controlling the operation of the device 4 and embodying the invention.

The valve device 2 may be of any suitable type having one position for establishing communication from the fluid pressure supply pipe 3 to the whistle 1 through which fluid under pressure is adapted to be supplied from said pipe to said whistle for effecting the operation thereof, and having another position for cutting off the supply of fluid under pressure to said whistle to prevent its operating.

The valve device 2 is adapted to be operated by a lever 6 fulcrumed at one end on a pin 7 and connected at the other end by a pin 8 to one end of a link 9 the other end of which is connected by a pin 10 to the end of a rod 11 connected to a piston 12 contained in the operating device 4.

The piston 12 has at one side a chamber 13 open to the atmosphere through a breather port 14 and containing a spring 15 acting on the piston. The piston 12 has at the opposite side a chamber 16 which is connected to a pipe 17 leading to the control device 5.

The control device 5 comprises a casing containing a signal or whistle control valve device 18 which comprises a piston 19 having at one side a chamber 20 containing a spring 21 acting on the piston and having at the opposite side a valve chamber 22 in constant communication through a passage and pipe 23 with any suitable source of fluid under pressure such as may be provided by a reservoir 24. The valve chamber 22 contains a slide valve 25 disposed between spaced shoulders on a stem 26 secured to the piston 19 so as to be moved with said piston.

The operation of the whistle control valve device 18 to effect operation of the whistle 1 is adapted to be controlled by a blast initiating valve device 27 and a blast repeater valve device 28.

The blast initiating valve device 27 comprises a valve 29 contained in a chamber 30 for controlling communication therefrom to a chamber 31. The chamber 30 is connected by passages 32 and 33 to the control piston chamber 20 and contains a spring 34 for seating the valve 29. The valve 29 has a stem extending through a suitable bore in the casing into the chamber 31 and there engaging the end of an operating stem 35 which extends to the exterior of the casing and which is adapted to be depressed to unseat the valve 29 against the spring 34. A valve 36 is provided on the stem 35 adapted to engage a seat formed in the casing when the valve 29 is unseated to prevent leakage of fluid under pressure.

from chamber 31 past the valve stem 35 to the atmosphere.

The valve stem 35 may be operated to unseat the valve 29 in any desired manner, as by pressure applied manually by the engineer, or if desired it may be operated automatically through the medium of suitable ramps (not shown) provided along the trackway. The particular means whereby the valve stem 35 is depressed is however not pertinent to the invention and a further description thereof is not essential.

The blast repeating valve device 28 comprises a movable abutment preferably in the form of a flexible diaphragm 38 having at one side a chamber 39 and at the opposite side a chamber 40 which is open to the atmosphere through an atmospheric port 41. A follower plate 42 is disposed in chamber 40 and is secured to the diaphragm 38, while a spring 43 in said chamber acts on the follower plate 42 for urging same and the diaphragm 38 to their normal position, as shown in the drawing.

Two poppet valves 44 and 45 are disposed in chambers 46 and 47, respectively, for controlling communication from said chambers to passages 48 and 49, respectively, leading to the atmospheric chamber 40. These valves are adapted to engage seat ribs provided in their respective chambers for closing communication therefrom to the chamber 40. The follower 42 is provided with two spaced stems 50 and 51 extending into the passages 48 and 49, respectively, and adapted, upon deflection of the diaphragm 38 against the opposing pressure of spring 43, to engage said valves and move same out of engagement with their respective seats.

A blast terminating valve device 52 is provided for effecting operation of the signal control valve device 18 to terminate signaling operation of whistle 1 at a predetermined time interval after operation of the initiating valve device 27 or repeating valve device 28.

The terminating valve device 52 comprises a flexible diaphragm 53 having at one side a chamber 54 and at the opposite side a chamber 55 open to the atmosphere through an atmospheric passage 56. A follower 57 disposed in the chamber 55 is secured to the diaphragm 53 and a spring 58 in said chamber acts on said follower in opposition to the pressure of fluid in chamber 54. A valve 59 is provided in the chamber 55 to control communication from said chamber to a passage 60. A valve 61 is provided in a chamber 62 for controlling communication therefrom to passage 60, and a spring 63 is provided in said chamber acting on valve 61 urging same to its seat. The valve 59 has a stem 64 which engages a stem 65 projecting from the valve 61, said stems being of such length as to unseat one of said valves when the other is seated. A stem 66 projecting from the follower plate 57 and engaging the valve 59 is provided for controlling the seating and unseating of the valves 59 and 61.

A valve device 67 is provided to operate at a certain time to modify the operation of the blast terminating valve device 52 so as to change the length of whistle blasts effected by the operation of the control valve device 18. The valve device 67, which may therefore be called the blast change device, comprises a piston 68 having at one side a chamber 69 containing a spring 70 acting on said piston and having at the opposite side a chamber 71 containing a slide valve 72 disposed between spaced shoulders on a stem 73

which projects from the piston 68, so that said slide valve will move with said piston.

The valve devices 74 and 75 are provided for controlling the operation of the blast change device 67. The device 74 comprises a piston 76 having at one side a chamber 77 containing a spring 78 acting on the piston and having at the opposite side a chamber 79 containing a slide valve 80 disposed between spaced shoulders on a stem 81 projecting from said piston, so that 10 said slide valve will move with said piston.

The valve device 75 comprises a piston 82 having at one side a chamber 83 and having at the opposite side a chamber 84 open to the atmosphere through an atmospheric passage 85. The 15 valve device 75 further comprises a valve 86 contained in a chamber 87 for controlling communication from said chamber to the atmospheric chamber 84. A spring 88 in the chamber 87 acts on the valve 86 urging it to its seat, while 20 a stop 89 extending into said chamber is adapted to be engaged by said valve for limiting unseating movement thereof. The piston 82 has a stem 90 adapted to engage the valve 86 for unseating said valve. A vent port in the form of a groove 25 91 is provided in the wall of the cylinder containing piston 82 and forms a vent communication from the chamber 84 to the atmospheric passage 85. The groove 91 is normally disconnected from the chamber 83 by the piston 82 but 30 is adapted to be opened to said chamber upon movement of said piston to unseat the valve 86.

A device 92 which may be termed a signal stop valve device is provided for causing the mechanism to cease operation after having effected the 35 operation of the whistle 1 to provide a predetermined series of blasts.

The signal stop valve device 92 comprises a piston 93 having at one side a chamber 94 containing a spring 95 acting on said piston and 40 having at the opposite side a valve chamber 96 containing a slide valve 97 disposed between spaced shoulders on a stem 98' projecting from the piston 93.

The pilot valve device 98 is provided for controlling the operation of the signal stop valve device 92. The pilot valve device 98 comprises a flexible diaphragm 99 having at one side a chamber 100 and at the opposite side a chamber 101 connected to the atmosphere through an atmospheric passage 102. A diaphragm follower 103 disposed in chamber 101 is secured to the diaphragm 99 and a spring 104 contained in chamber 101 acts on said follower for urging said diaphragm in the direction of chamber 100. The 55 diaphragm 99 is provided for controlling the operation of two oppositely seating valves 105 and 106, the valve 105 being contained in a chamber 107 and the valve 106 being contained in the chamber 101. A stem 108 forms an operating 60 connection between valves 105 and 106 and is of such length that when one of the valves is seated, the other valve is unseated. A spring 109 in chamber 107 acts on the valve 105 urging said valve to its seat and the valve 106 away from its seat. The diaphragm follower 103 is provided with a stem 110 engaging the valve 106 and operative upon deflection of the diaphragm 99 against spring 104 to seat the valve 106 and 70 unseat the valve 105.

A device 111 is provided which is adapted to operate, after the mechanism has effected through the medium of the whistle 1 a predetermined series of blasts, to recondition the mech- 75

anism for operating to repeat such series of blasts at the next crossing.

The device 111 may be called a reset valve device and comprises a piston 112 having at one side a chamber 113 and having at the opposite side a chamber 114 connected by a passage 115 to chamber 31 in the initiating valve device 27. The piston 112 has a stem 116 slidably mounted in a suitable bore extending through a partition wall and leading to a chamber 117 which is in constant communication with the atmosphere through a passage 118. A groove 119 is provided longitudinally in the stem 116 forming an always open communication between chambers 114 and 117. A cross-head 120 having two spaced fingers 121 and 122 is provided in chamber 107 and is adapted to be operated by piston stem 116 upon movement of the piston 112 toward the right hand to unseat two valves 123 and 124 against the opposing seating pressures of springs 125 and 126, respectively. The valve 123 is contained in a chamber 127 and is provided for controlling communication therefrom to chamber 117, while the valve 124 is contained in a chamber 128 and is adapted to control communication from said chamber to chamber 117.

A by-pass valve 129 is provided which comprises a piston 130 having at one side a chamber 131 in constant communication with the atmosphere through an atmospheric passage 132 and containing a spring 133 acting on said piston. The piston 130 has at the opposite side a chamber 134 in constant communication with the supply reservoir 24 through a relatively large bore 135 and passage and pipe 23. A valve 136 is contained in a chamber 137 for controlling communication from said chamber to the bore 135 and a spring 138 in said chamber acts to urge the valve 136 to its seated position. The piston 130 has a stem 139 extending through the bore 135 and adapted to engage the valve 136 for unseating said valve upon movement of the piston 130 in a direction toward the left hand. The spring 138 acting on the valve 136 exerts a less pressure on the valve 136 than spring 133 exerts on the piston 130 so that when the mechanism is void of fluid under pressure, spring 133 will maintain the piston 130 in sealing engagement with a gasket 140 and in this position will hold the valve 136 unseated.

In operation, fluid under pressure is supplied to the supply reservoir 24 from any suitable source and from thence flows through pipe and passage 23 to valve chamber 22 of the whistle control valve device 18 and to the relatively large bore 135 in the valve device 129.

With the whistle control piston 19 in the position shown in the drawing fluid under pressure supplied to chamber 22 is permitted to flow through a relatively small by-pass groove 141 to piston chamber 20. With the valve 136 unseated, fluid under pressure supplied from the reservoir 24 to the bore 135 is permitted to flow at a relatively rapid rate to chamber 137 and from thence through passage 33 to piston chamber 20 and also from passage 33 to valve chamber 30 in the initiating valve device 27. Due to the supply of fluid under pressure past valve 136 to piston chamber 20, the pressure of fluid in chamber 20 builds up at substantially the same rate as that in valve chamber 22 and thus prevents, during this initial charging operation, the development of a sufficient differential of pressures on the piston 19 to move said piston toward the left hand against the opposing pressure of spring 21.

When the pressure thus obtained in piston chamber 20, valve chamber 137 and in chamber 134 acting on the left hand face of the by-pass piston 130 becomes sufficient to overcome the opposing pressure of spring 133, said piston is moved out of sealing engagement with gasket 140 and to its right hand position in which it engages and seals against a gasket 142. This movement of piston 130 permits spring 138 to seat valve 136 and thereby close this communication between the valve chamber 22 and the piston chamber 20 following which equalization of the fluid pressures in valve chamber 22 and piston chamber 20 occurs through the by-pass groove 141.

At this point it is desired to point out that the pressure of spring 138 on valve 136 is sufficient to prevent unseating of said valve upon any reduction in pressure effected in piston chamber 20 and thereby in valve chamber 137 during operation of the mechanism as will hereinafter be described.

The piston 130 seals against the gasket 142 in its right hand position, as above described, in order to prevent leakage of fluid under pressure from the bore 135 and thereby from the supply reservoir 24 past said piston to the atmospheric chamber 131 and thereby to the atmosphere through passage 132.

Fluid at the pressure in the supply reservoir 24 supplied to the control valve chamber 22 is also supplied from said chamber to a passage 143 and through this passage to valve chamber 71 of the blast change device 67, valve chamber 96 of the valve device 92, valve chamber 107 of the valve device 98, valve chamber 79 of the valve device 74 and to valve chamber 62 of the valve device 52.

In the drawing, the various devices of the control valve device 5 are shown in their normal positions to which they are moved after said device has been operated to effect a series of signal blasts, as will be hereinafter described.

The whistle control valve device 18 has, beside the normal position shown in the drawing, another position defined by the engagement of the piston 19 with a gasket 144, this other position being the position for effecting operation of the whistle 1.

In the normal or non-operating position of the piston 19 and its slide valve 25, piston chamber 16 of the cylinder device 4 is vented to the atmosphere through pipe and passage 17, a cavity 145 in slide valve 25 and an atmospheric passage 146. This permits spring 15 acting on the piston 12 to move the piston 12 and thereby the whistle operating lever 6 to a position in which the valve device 2 closes communication from the fluid pressure supply pipe 3 to the whistle 1, so that the whistle 1 will not operate. When the whistle control valve device 18 is moved to the signaling position in which piston 19 engages the gasket 144, a port 148 in the slide valve 25 registers with the passage 17 and permits fluid under pressure from valve chamber 22 to flow through said passage to cylinder 16 and therein act on the piston 12 to move said piston against the pressure of spring 15 toward the right hand and thereby operate the lever 6 and valve device 2 to open communication from the fluid pressure supply pipe 3 to the whistle 1, and through this communication fluid under pressure is supplied to said whistle for effecting a signal blast.

With the parts of the control valve device 5 in their normal position as shown in the drawing and with fluid under pressure supplied from the reservoir 24 to the various chambers in said valve 75

device as hereinbefore described, if it is desired to effect a signal, consisting of two long and two short blasts, upon the approach to a grade crossing, the plunger 35 of the initiating valve device 5 27 is depressed, in any desired manner.

This operation of plunger 35 seats the valve 36 and unseats the valve 29 which vents fluid under pressure from piston chamber 20 through passages 33 and 32, chamber 30, past the valve 10 29 to chamber 31 and from thence through passage 115 to chamber 114 in the reset device 111 and from thence through groove 119 in the piston stem 116 to chamber 117 and from thence to the atmosphere through passage 118. This 15 venting of fluid under pressure from piston chamber 20 reduces the fluid pressure therein to a sufficient degree below the opposing fluid pressure in chamber 22 acting on the piston 19, that a sufficient differential of fluid pressures is obtained to move said piston toward the left hand against the opposing pressure of spring 21 and into engagement with the gasket 144. With the piston 19 and slide valve 25 thus moved to the signaling position, fluid under pressure is supplied from chamber 22 through port 148 to passage 17 and from thence to the operating cylinder 4 for effecting operation of the valve device 2 to supply fluid under pressure to the whistle 1 for effecting operation thereof.

30 In the signaling position of the piston 19 and slide valve 25 the piston chamber 20 is vented to the atmosphere through choke 149, passage 150, a cavity 151 in said slide valve and an atmospheric passage 152' and since the control of 35 this communication is independent of the initiating valve device 27, it permits the initiating device 27 to be relieved of operating pressure and thereby permits spring 34 to seat the valve 29 immediately upon movement of the slide valve 40 25 to the signaling position, and since such movement occurs promptly upon unseating of the valve 29, it will be evident that only momentary unseating thereof is required to effect movement of the piston 20 to the signaling position.

45 In the signaling position of slide valve 25 a port 152 therein registers with a passage 153 and through this communication fluid under pressure is supplied from valve chamber 22 to passage 153 from whence it flows through a choke 154 to a timing reservoir 155 which is in communication through a passage 156 with chamber 54 at the lower face of diaphragm 53 in the blast terminating valve device 52, and with valve chamber 47 in the blast repeating 50 55 valve device 28. The size of the choke 154 and the volume of the reservoir 155 are so related that by the time the whistle 1 has been operated to effect a blast of the desired duration, sufficient pressure will be obtained in reservoir 155 and in chamber 54 acting on the diaphragm 53 to deflect said diaphragm upwardly against the opposing pressure of the spring 58, and this movement acts to seat the valve 59 and unseat the valve 61.

60 65 The unseating of valve 61 permits fluid under pressure to flow from chamber 62 to passage 60 and from thence past a check valve 157 and through a passage 158 to the piston chamber 20. The rate at which fluid under pressure is thus supplied to piston chamber 20 sufficiently exceeds the venting capacity of choke 149 to promptly build up sufficient pressure in chamber 20 to permit spring 21 to move the piston 19 and thereby the slide valve 25 to the right 70 75 hand or non-whistling position. In this position

the port 148 is moved out of registry with passage 17 thus cutting off the supply of fluid under pressure to the whistle operating cylinder 4, and passage 17 is vented to the atmosphere through cavity 145 in slide valve 25 and atmospheric passage 146, and this permits the operating cylinder 4 to operate the valve 2 to cut off the supply of fluid under pressure for operating the whistle 1, as hereinbefore described. The whistle 1 is thus stopped from operating. 10

In the right hand or non-whistling position of the device 18 a cavity 159 in slide valve 25 connects passage 153 to a passage 160, which permits fluid under pressure in the reservoir 155 to flow through a passage 161', past check valve 162 by-passing the choke 154, to passage 153 and from thence through cavity 159 to passage 160 and from thence through a choke 161, past a check valve 162' and through a passage 163 to a reservoir 164 which communicates through a 20 passage 165 with the diaphragm chamber 39 in the blast repeating valve device 28.

The fluid under pressure is thus permitted to flow from the reservoir 155 to the reservoir 164 at a rate determined by the size of the choke 161. 25 The consequent reduction in pressure in reservoir 155 and in chamber 54 of the blast terminating valve device 52 permits spring 58 to deflect the diaphragm 53 downwardly and this permits spring 63 to seat the valve 61 and unseat the valve 59, thus cutting off the supply of fluid under pressure to the piston chamber 20 by way of the ball valve 157.

The size of the choke 161 and the volume of the timing reservoir 164 are so related to each other and the volume of the timing reservoir 155 that after a predetermined interval of time, a sufficient pressure is obtained in reservoir 164 and in chamber 39 acting on the diaphragm 38 to move said diaphragm upwardly against the 40 opposing pressure of spring 43, and this upward movement of said diaphragm acts to unseat the valves 44 and 45. The unseating of the valve 45 suddenly vents the fluid under pressure remaining in the reservoir 155 through the passage 45 156 and chamber 47 to the chamber 40 and from thence to the atmosphere through passage 41. The unseating of the valve 44 acts to vent fluid under pressure from the piston chamber 20 of the whistle control valve device 18 through passage 166, a choke 167, and valve chamber 46 to chamber 49 and from thence to the atmosphere through atmospheric passage 41. This venting of fluid under pressure from piston chamber 20 is adapted to effect sufficient reduction in pressure therein to cause the whistle control valve piston 19 and slide valve 25 to again move to their left hand or whistling position, but the choke 167 is provided to sufficiently delay obtaining said reduction in pressure in piston 60 chamber 20 as to prevent movement of the piston 19 and slide valve 25 to the whistling position before the timing reservoir 155 is completely vented by way of the valve 45, and so that said reservoir will thus be in condition to properly measure the duration of the subsequent or second long blast of the whistle. 65

In the signaling position of the valve device 18 fluid under pressure is again supplied through the port 152 in slide valve 25 to passage 153 and from thence through the choke 154 to the timing reservoir 155, and after a certain degree of pressure is obtained in said reservoir acting on diaphragm 53 of the blast terminating valve 52, the blast terminating valve 52 is again operated to 70 75

supply fluid under pressure to the piston chamber 20 and thereby effect movement of the piston 19 and slide valve 25 to the non-signaling position. It will be noted the whistle control valve device 18 remains in the left hand or signaling position the same length of time while effecting the second blast from whistle 1 as just described, as when effecting the initial blast, this length of time, or in other words, the duration of the whistle blast being controlled in both cases by the time required to charge the reservoir 155 through choke 154.

Upon movement of the whistle control valve device 18 to the normal position at the end of the second blast of whistle 1, fluid under pressure is again permitted to flow from the timing reservoir 155 to the timing reservoir 164, and when sufficient pressure is obtained in the reservoir 164 and in the connected diaphragm chamber 39 to operate the blast repeating valve device 28, the blast repeating valve device is again operated to unseat the valves 44 and 45 to effect venting of fluid under pressure from the timing reservoir 155 and from piston chamber 20 of the whistle control valve device 18 for initiating another blast of the whistle 1 as hereinbefore described.

When the control valve device 18 is in the left hand position effecting a signal blast a cavity 163 in the slide valve 25 connects passage 169 from the timing reservoir 164 to a passage 169 leading to piston chamber 83 in the valve device 75. Fluid under pressure then flows from the reservoir 164 to chamber 83 and acts to move the piston 82 downwardly and open the atmospheric groove 91 to chamber 83, and through this communication fluid under pressure is vented from the timing reservoir 164 while the control valve device 18 is in the signaling position. In this manner the reservoir 164 is conditioned, while the whistle 1 is being operated to effect a signal blast, to time the interval between blasts upon movement of the piston 19 and slide valve 25 from their signaling to their non-signaling position.

When the valve device 18 is moved to the non-signaling position at the termination of the second blast of whistle 1, the reservoir 155 is again connected to the reservoir 164 and when sufficient pressure is obtained in reservoir 164 and in diaphragm chamber 39 of the repeater valve device 28 to overcome the pressure of spring 43, the diaphragm 38 is again deflected to unseat the valves 44 and 45. The unseating of the valve 44 acts to vent fluid under pressure from piston chamber 20 for again effecting movement of the control valve device 18 to signaling position, while the unseating of valve 45 acts to vent the fluid under pressure from reservoir 155 to condition said reservoir for measuring the duration of the next blast of the whistle 1, as hereinbefore described.

From the above description it will be noted that the length or duration of each of the initial two blasts of the whistle 1 is controlled by the build up in pressure in the reservoir 155 through the choke 154 and is terminated by the valve device 52 when a predetermined pressure is obtained in said reservoir. The interval between blasts is controlled by the build up of pressure in reservoir 164 through the choke 161 and is terminated by the operation of valve device 28 when a certain predetermined pressure is obtained in reservoir 164. The operation of the valve device 28 vents fluid under pressure from the reservoir 155 so as to condition said reservoir for timing the

duration of the succeeding blast of the whistle, and while the valve device 18 is in the signaling position the reservoir 164 is vented by way of the valve device 75 so that said reservoir will be in condition for timing the interval between blasts 5 upon subsequent movement of the control valve device 18 to the non-signaling position.

In the normal position of the valve device 74 a port 170 in the slide valve 80 permits fluid supplied from the supply reservoir 24 to valve chamber 79 to flow to passage 171 and from thence to piston chamber 69 in the valve device 67. The fluid pressure thus obtained in piston chamber 69 is the same as that acting in valve chamber 11 and permits spring 79 to hold the piston 68 15 in the position shown in the drawing.

While the whistle valve device 18 is operating to effect the initial two blasts of the whistle 1, each time the whistle valve device moves to the whistling position, a port 172 in the slide valve 25 20 registers with a passage 173 containing a choke 174 and through this communication fluid under pressure is supplied from valve chamber 22 to a reservoir 175 which is in communication through passage 176 with piston chamber 71 of the valve 25 device 74. While effecting the initial two blasts of the whistle 1 sufficient pressure is obtained in reservoir 175 and piston chamber 71 of the valve device 74, as aided by spring 78, to overcome the opposing pressure of fluid in valve 30 chamber 19 on the piston 76 and move said piston from the position shown in the drawing to a right hand position in which it engages the casing. This movement of the piston 76 shifts the slide valve 81 from the position shown in the drawing 35 to a position in which a cavity 177 in said slide valve connects passage 171 from piston chamber 69 in the valve device 67 to a passage 178 leading to valve chamber 87 in the valve device 75.

When the valve device 75 is operated by fluid 40 under pressure supplied from the timing reservoir 164 upon movement of the signal control valve device 18 to the signaling position following the interval after the second blast of whistle 1, the unseating of the valve 86 in the device 75 45 vents fluid under pressure from passage 178 and thereby from piston chamber 69 of the valve device 67 to chamber 84 at the lower side of the piston 82 and from thence through the groove 91 to the atmosphere through the atmospheric 50 passage 85. The consequent reduction in pressure in piston chamber 69 of the valve device 67 permits the pressure of fluid in the valve chamber 71 to move the piston 68 toward the left into engagement with a gasket 179. 55

With the slide valve 72 of the valve device 67 moved to this left hand position, a cavity 180 therein connects a passage 181 to a passage 182 which communicates through a choke 183 with passage 156 leading to the timing reservoir 155. 60 The passage 181 connects with passage 153 in front of the choke 154 thereby establishing a communication from passage 153 around the choke 154 and through the choke 183 to the reservoir 155, it being noted that the choke 183 is 65 thus connected in parallel with the choke 154.

When the whistle control valve device 18 moves to the signaling position following the interval after the second blast of whistle 1, fluid under pressure supplied to passage 153 flows through 70 choke 154 to the timing reservoir 155 and at the same time through passage 181, cavity 180 in slide valve 72 to passage 182 and from thence through choke 183 and passage 156 to the timing reservoir 155. The timing reservoir 155 is thus 75

charged through the two chokes 154 and 183, arranged in parallel, and the pressure in said reservoir builds up more rapidly than when charged through the choke 154 by itself as occurred while 5 effecting the initial two blasts of the whistle 1. As a result, sufficient pressure is obtained in diaphragm chamber 54 for operating the valve device 52 to effect movement of the signal control valve device 18 to its non-signaling position sooner than 10 when effecting the initial two blasts of the whistle 1. In other words, due to the additional supply of fluid under pressure to the timing reservoir 155 through the choke 183 while effecting the third signal blast of whistle 1, the third blast 15 is terminated a shorter time after being initiated than the initial two blasts, the length of which was controlled by the charging of the reservoir 155 through only the choke 154.

When the signal control valve device 18 is 20 moved to the non-signaling position to terminate the third blast of whistle 1 as just described, the supply of fluid under pressure from valve chamber 22 to the timing reservoir 155 is cut off and said reservoir is again connected to the timing 25 reservoir 164. The consequent reduction in pressure in timing reservoir 155 and diaphragm chamber 54 of the blast terminating valve 52 permits closure of the valve 61 which cuts off the supply of fluid under pressure to the piston chamber 20 and when a predetermined pressure is obtained in the timing reservoir 164 by flow from the reservoir 155 the blast repeating valve device 28 is again operated to vent the timing reservoir 155 and to effect movement of the signal valve device 18 to the signaling position to initiate the 30 fourth blast of whistle 1. In this position fluid under pressure is again supplied from the valve chamber 22 through port 152 in the slide valve 25 and both chokes 154 and 183 to the timing reservoir 155 and when a predetermined pressure is obtained therein the valve device 52 is again operated to effect movement of the signal control valve device 18 to its non-signaling position, thus 35 terminating the fourth blast of whistle 1. This fourth blast of whistle 1 is of the same length as the third blast which was shorter than the initial two blasts; thus as described, the mechanism has automatically operated to effect a signal comprising two long and two short blasts, and the same interval has been provided between 40 all of the blasts by the reservoir 164 and choke 161.

As hereinbefore described, fluid under pressure is supplied from the valve chamber 22 of the signal control valve device 18 to the timing reservoir 175 whenever the signal control valve device 18 is in the signaling position. The choke 174 in this communication is so proportioned to the volume of the reservoir 175 that before completion 45 of the second short blast of the whistle 1 a sufficient pressure will be obtained in the reservoir 175 and connected diaphragm chamber 100 of the valve device 98 to deflect the diaphragm 99 against the opposing pressure of spring 104 and thereby seat the valve 106 and unseat the valve 105.

With the valve 105 unseated fluid under pressure is supplied from chamber 107 to a passage 185 which leads to the seat of the slide valve 25. 50 When the slide valve 25 is moved to the non-signaling position at the termination of the second short blast of the whistle 1, a cavity 186 in said slide valve connects passage 185 to a passage 181 so that fluid under pressure supplied to 55 passage 185 by operation of the valve device 98

flows to passage 187 and from thence to piston chamber 94 of the signal stop valve device 92 and to the piston chamber 113 of the reset valve device 111.

The pressure of fluid thus attained in piston chamber 94 acting with spring 95 overcomes the opposing pressure of fluid in valve chamber 96 acting on the piston 93 and moves said piston and the slide valve 97 from the position shown in the drawing to its left hand position in which a cavity 190 in said slide valve connects a passage 191 from the timing reservoir 164 to an atmospheric passage 192. Through the communication just described the timing reservoir 164 is connected to the atmosphere at the termination of the second short blast of the whistle 1, so that the fluid under pressure supplied to said reservoir from the timing reservoir 155 cannot build up sufficient pressure therein to again effect operation of the repeating valve device 28, and as a result, said device and the signal control valve device 18 remain in their normal positions after the fourth blast of the whistle 1 has terminated. It will be noted that since the timing reservoir 155 is connected to the reservoir 164 with the signal control valve device 18 in the non-signaling position, fluid under pressure will be vented from both of these reservoirs by way of the valve device 92 when in its left hand position.

The pressure of the fluid supplied to chamber 113 in the reset valve device 111 acting on the piston 112 moves said piston from the position shown in the drawing towards the right hand into engagement with a gasket 193. This movement of the piston 112 acts through the cross-head 120 and pins 121 and 122 to unseat the valves 123 and 124, respectively. The unseating of the valve 123 opens a vent communication to diaphragm chamber 100 of the valve device 98 and to the timing reservoir 175 and through this communication fluid under pressure is vented from said chambers to chamber 117 and from thence to the atmosphere through the atmospheric passage 118.

When the pressure in diaphragm chamber 100 is thus reduced sufficiently, spring 104 deflects diaphragm 99 downwardly permitting seating of the valve 105 by spring 109. As the valve 105 is seated the valve 106 is unseated and past valve 106 fluid under pressure is vented from piston chamber 113 of the reset valve device 111 and from piston chamber 94 of the valve device 92 by way of passage 181, cavity 186 in the slide valve 25, passage 185, through chamber 101 and from thence through passage 102 to the atmosphere. When the fluid under pressure is thus vented from piston chamber 94 of the valve device 92 the supply reservoir pressure acting in valve chamber 96 of said device promptly overcomes the opposing pressure of spring 95 on the piston 93 and moves said piston and the slide valve 97 to the position shown in the drawing in which communication between passage 191 and the atmospheric exhaust passage 190 is closed. The passage 191 is, however, maintained open to the atmosphere past the unseated valve 124 in the reset valve device 111, chamber 117 and the atmospheric passage 118, after the valve device 92 moves to its right hand or normal position. The fluid under pressure remaining in the timing reservoirs 164 and 155 at the time of the movement of the valve device 92 to its right hand position, is therefore completely vented past the valve 124 in the reset valve device 111, while past the valve 123 in said device, the fluid under pressure is completely

vented from the reservoir 175, piston chamber 77 in the valve device 74, and from diaphragm chamber 100 in the valve device 98.

When the pressure of fluid in piston chamber 77 of the valve device 74 is reduced sufficiently, as just described, the pressure of fluid in valve chamber 79 moves the piston 76 to its normal or left hand position against the opposing pressure of spring 78 and in this position the slide valve 81 supplies fluid under pressure through port 170 therein to passage 171 and from thence to piston chamber 69 of the valve device 67. When the pressure of fluid thus obtained in chamber 69 becomes sufficient, it acting in conjunction with spring 78 moves the piston 68 and slide valve 72 from the left hand to the right hand position in which communication is closed between passages 181 and 182, so that the choke 183 will be initially ineffective when the valve device 5 again operates upon the approach to a grade crossing.

The valves 123 and 124 of the reset valve device 111 are relatively small and the pressure of the springs 125 and 126, respectively, on said valves is only sufficient substantially to seat said valves, and the combined pressure of these springs is not sufficient to move the piston 112 out of its right hand position after the venting of fluid under pressure from chamber 113 at the left hand face of said piston by the operation of the valve device 98. As a result, the valves 123 and 124 remain open while the valve device 5 is not being operated to effect a signal, the valve 123 thereby maintaining the reservoir 175, piston chamber 77 and diaphragm chamber 100 at atmospheric pressure, while the valve 124 acts to maintain the timing reservoirs 164 and 155 at atmospheric pressure, thereby maintaining the mechanism in proper condition to operate again, when required.

It is on account of the relatively small flow capacity of the valve 124 that the valve device 92 is provided to operate upon completion of the series of signal blasts to open a relatively large vent from the timing reservoir 164 in order to insure that a sufficient pressure will not be obtained in said reservoir and in the diaphragm chamber 39 of the repeating valve device 28 to operate said device to cause another signal blast to be effected.

It will be evident that while the valve device 92 is provided for venting fluid under pressure from the timing reservoir 164, so as to prevent a sufficient pressure being obtained therein to operate the valve device 28 at the termination of the desired series of signal blasts, it is not necessary to further reduce the pressure in the timing reservoir 164, since the pressure therein would be reduced upon the next operation of the whistle control valve device 18 to effect a signal, by way of the valve device 75. The vent by way of the valve 124 in the reset valve device 111 is not therefore primarily to vent the timing reservoir 164 but is to vent the timing reservoir 155 which is connected to reservoir 164 through the whistle control valve device 18 in its normal position, so that the timing reservoir 155 will be in condition to properly control the length of the initial whistle blast upon operation of the mechanism at the approach to the next grade crossing.

When it is desired to cause the valve device 5 to operate to effect another series of blasts of the whistle 1, the initiating valve device 27 is again operated to vent fluid under pressure from the piston chamber 20, past the valve 29 to passage 115 and from thence to chamber 114 at the right hand face of the piston 112 of the reset valve de-

vice 111. The fluid under pressure thus obtained in chamber 114 promptly moves the piston 112 out of its right hand position, shown in the drawing, and to its left hand position and then flows from said chamber through groove 119 to chamber 117 and thence to the atmosphere through the atmospheric port 118, as hereinbefore described. This movement of the piston 112 to its left hand position permits the springs 125, 126 to seat the valves 123 and 124, respectively, so that the timing reservoir 175 may become charged for controlling the operation of the valve devices 74 and 98, and so that the timing reservoir 164 may be in condition to function for controlling the valve device 28, as hereinbefore described.

From the above description it will be noted that a valve mechanism controlled completely by fluid pressure is provided which is automatically operative to provide a desired series of signal blasts at a grade crossing or the like.

This mechanism comprises a whistle control valve device 18 having a signaling position for effecting operation of the whistle 1 and having a non-signaling position in which it is normally carried and to which it is moved to stop operation of the whistle 1. The initiating valve device 27 is provided to cause the whistle control valve device 18 to operate to effect the initial blast of a desired series of blasts, while the valve device 28 is provided for causing the whistle control valve device 18 to effect the succeeding blasts of the series, after a time interval between blasts determined by the volume of reservoir 164 and choke 161. The valve device 52 acts to terminate the blasts after a length of time determined by the volume of reservoir 155 and the flow capacity of the choke 154 for the first two long blasts, and by the added flow capacity of choke 183 for the subsequent, two short blasts. The choke 183 is cut in at the proper time by the timed operation of the valve devices 74 and 67 as controlled by the charging of reservoir 175 through the choke 174, and by the operation of the valve device 75 as controlled by the operation of the control valve device 18.

The valve device 98 acts at the proper time to effect the operation of the valve device 92 to prevent further operation of the valve device 28 and thus terminates the operation of the valve device 18 at the completion of the desired series of blasts, while the valve device 111 under the control of the initiating valve device 27 acts to recondition the mechanism for effecting a signal at the next grade crossing, and also acts to prevent leakage of fluid under pressure within the mechanism from affecting the succeeding operation thereof.

It will be evident from the above description that the operation of the initiating valve device 27 may be effected in any desired manner and it will be further evident that the whistle control valve device 18 may control the operation of any desired type of signal device, the whistle device 1 being shown merely for the purpose of illustration.

While one illustrative embodiment of the invention has been described in detail, it is not the intention to limit its scope to that embodiment or otherwise than by the terms of the appended claims.

Having now described my invention, what I claim as new and desire to secure by Letters Patent, is:

1. In combination, a signal device, control means operative to control operation of said signal

device, a device having a normal position and operative upon movement from said position to initiate the operation of said control means and then returnable to said position, and fluid pressure controlled mechanism set in operation upon the operation of the initiating device and operative after return of said initiating device to said normal position for automatically effecting intermittent operation of said control means, said fluid pressure controlled mechanism comprising means controlled by variations in fluid pressure and operative automatically, after said signal device is operated to effect a blast of predetermined length, to effect the operation of said control means to cause said signal device to cease operating, and other means controlled by variations in fluid pressure and operative automatically a predetermined interval of time after the signal device has ceased operating, to cause said control means to again operate to cause said signal device to effect another signal blast.

2. In combination, a signal device, valve means operative to control operation of said signal device, a device movable to a certain position to initiate the operation of said valve means and then movable out of said position, and fluid pressure controlled mechanism set in operation upon the operation of the initiating device and automatically operative after movement of said initiating device out of said position for automatically effecting intermittent operation of said valve means, said fluid pressure controlled mechanism comprising means controlled by variations in fluid pressure and operative automatically, after said signal device is operated to effect a blast of predetermined length, to effect the operation of said valve means to cause said signal device to cease operating, and other means controlled by variations in fluid pressure and operative automatically a predetermined interval of time after the signal device has ceased operating, to cause said valve means to again operate to cause said signal device to effect another signal blast, both of said means being controlled by said valve means.

3. In combination, a signal device, control means operative to control operation of said signal device, a device movable to a certain position to initiate the operation of said control means and then movable out of said position, a fluid pressure controlled device operative automatically, a predetermined period of time after said control means is operated to cause said signal device to operate, to effect operation of said control means to stop operation of said signal device, and fluid pressure controlled means operative automatically a predetermined period of time after stopping said signal device and with the initiating device moved out of said certain position to effect operation of said control means to cause said signal device to again operate.

4. In combination, a signal device, valve means operative to control the operation of said signal device, a device movable to a certain position to initiate the operation of said valve means and then movable out of said position, mechanism controlled by fluid under pressure supplied through said valve means, after the operation of said valve means in initiated and only with said device moved out of said position, for automatically effecting the operation of said valve means to cause said signal device to effect a predetermined series of successive signal blasts, and means controlled by fluid under pressure supplied through said valve means and operative a predetermined

period of time after operation of the initiating device for preventing further operation of said valve means to effect operation of said signal device.

5. In combination, a signal device, valve means operative in accordance with variations in fluid pressure thereon for effecting operation of said signal device to produce a series of successive signal blasts, means movable to a certain position to initiate the operation of said signal device to produce a blast and then movable out of said position, fluid pressure controlled means controlled by said valve means and set in operation upon the operation of said signal device being initiated and operative automatically only with the initiating means moved out of said position for effecting said variations in fluid pressure on said valve means, and means operative automatically upon the completion of said series of signal blasts to prevent further operation of said valve means to effect operation of said signal device.

6. In combination, a signal device, valve means operative in accordance with variations in fluid pressure thereon for controlling operation of said signal device, means movable to a position for initiating the operation of said valve means to effect the operation of said signal device to produce a blast and then automatically movable out of said position, means controlled by said valve means and operative automatically only with the initiating device moved out of said position to effect said variations in fluid pressure on said valve means for effecting operation thereof to stop operation of said signal device a predetermined interval of time after starting and to start said signal device operating a predetermined interval of time after stopping, means for controlling said intervals of time, and means controlled by fluid under pressure operative automatically at the completion of a predetermined series of signal blasts to prevent further operation of said valve means.

7. In combination, a signal device, valve means operative in accordance with variations in fluid pressure thereon for controlling operation of said signal device, means operative to initiate the operation of said signal device to produce a blast, means controlled by fluid under pressure for controlling said valve means and operative automatically to effect operation thereof to stop operation of said signal device a predetermined interval of time after stopping and to start said signal device operating a predetermined interval of time after stopping, fluid pressure controlled means for controlling the interval of time between the starting and stopping of said signal device, valve means operative automatically to vary the interval of time between the starting and stopping of the signal device so as to produce signal blasts of different predetermined lengths, and means controlled by fluid under pressure automatically operative at the completion of a predetermined series of signal blasts for preventing further operation of said valve means to effect operation of said signal device.

8. In combination, a signal device, valve means movable to a signaling position for effecting operation of said signal device to produce a signal blast and movable to a normal position for preventing said signal device from operating, initiating means movable from one position to another position to effect movement of said valve means to signaling position for initiating the operation thereof, said initiating means being then

movable back to said one position, means controlled by fluid under pressure and set in operation upon movement of said valve means to the signaling position and automatically operative after a predetermined interval of time and with said initiating means in said one position to effect movement of said valve means to said normal position, means set in operation upon movement of said valve means to said normal position and automatically operative after a predetermined interval of time and with said initiating means in said one position to effect movement of said valve means to said signaling position, and means cooperative with said valve means for controlling said intervals of time.

9. In combination, a signal device, valve means movable to a signaling position for effecting operation of said signal device to produce a signal blast and movable to a normal position for preventing said signal device from operating, initiating means movable from one position to another position to effect movement of said valve means to the signaling position for initiating operation of said valve means said initiating means being then movable back to said one position, a chamber, fluid pressure controlled means operative upon a predetermined increase in fluid pressure in said chamber to effect movement of said valve means from said signaling position to said normal position, means cooperative with said valve means for controlling the increase in pressure in said chamber, means operative upon movement of said valve means to said normal position to vent fluid under pressure from said chamber, means automatically operative a predetermined interval of time after movement of said valve means to said normal position and with said initiating means in said one position to effect movement of said valve means to said signaling position, and means for controlling said interval of time.

10. In combination, a signal device, valve means movable to a signaling position for effecting operation of said signal device to produce a signal blast and movable to a normal position for preventing said signal device from operating, means operative to effect movement of said valve means to the signaling position for initiating operation of said valve means, a chamber, fluid pressure controlled means operative upon a predetermined increase in fluid pressure in said chamber to effect movement of said valve means from said signaling position to said normal position, means cooperative with said valve means in the signaling position thereof for providing a chosen rate of supply of fluid under pressure to said chamber, flow control means operative to increase the rate of supply of fluid under pressure to said chamber, means for rendering said flow control means effective when said valve means is moved to said signaling position a predetermined interval of time after the operation of said valve means is initiated, means controlled by fluid under pressure supplied through said valve means upon movement thereof to said normal position for effecting movement of said valve means to the signaling position after a predetermined lapse of time in said normal position, and means for measuring said lapse of time.

11. In combination, a signal device, valve means movable to a signaling position for effecting operation of said signal device to produce a signal blast and movable to a normal position for preventing said signal device from operating, means operative to effect movement of said valve means to the signaling position for initiating operation

of said valve means, a chamber, fluid pressure controlled means operative upon a predetermined increase in fluid pressure in said chamber to effect movement of said valve means from said signaling position to said normal position, means cooperative with said valve means in the signaling position thereof for controlling the supply of fluid under pressure to said chamber at a predetermined rate, flow control means operative to increase the rate of supply of fluid under pressure to said chamber, a valve controlled by said valve means, a valve device controlled by the pressure of fluid in said chamber and cooperative with said valve upon a predetermined variation in fluid pressure in said chamber and upon movement of said valve means to said signaling position to render said flow control means effective, said valve means controlling the pressure of fluid in said chamber and being operative to effect said variation in fluid pressure a predetermined interval of time after the initiation of its operation, another chamber, means operative upon a predetermined variation in fluid pressure effected in said other chamber by said valve means when in said normal position for effecting movement of said valve means to said signal position, and means operative in the signal position to vent fluid under pressure from the last mentioned chamber.

12. In combination, a signal device, valve means having a signaling position for effecting operation of said signal device and a normal position for preventing operation of said signal device, means operative to initiate the operation of said valve means to operate said signal device, a fluid pressure controlled valve device operative to effect movement of said valve means to the signaling position, fluid pressure controlled means operative to effect movement of said valve means to its normal position, means operative in the normal position of said valve means to condition said fluid pressure controlled valve device to operate a predetermined period of time after movement of said valve means to said normal position, means operative in the signaling position of said valve means to condition said fluid pressure controlled means to operate after a predetermined lapse of time from the movement of said valve means to the signaling position, and means operative to vary said lapse of time a predetermined interval of time after the initial movement of said valve means to the signaling position.

13. In combination, a signal device, valve means having a signaling position for effecting operation of said signal device and a normal position for preventing operation of said signal device, means for effecting the initial movement of said valve means to the signaling position, a chamber the pressure of fluid in which is varied upon movement of said valve means to said signaling position, a valve device controlled by the pressure of fluid in said chamber and operative upon a predetermined variation in the pressure therein to effect movement of said valve means to said normal position, a timing reservoir in which the pressure of fluid is varied by said valve means in its normal position, a valve device operative upon a predetermined variation in the pressure in said timing reservoir to effect movement of said valve means to the signaling position, means controlled by said valve means for varying the pressure of fluid in said chamber and reservoir, and means controlled by said valve means operative a predetermined period of time after the operation of

said valve means is initiated to prevent said predetermined variation in pressure in said timing reservoir upon movement of said valve means to said normal position.

5 14. In combination, a signal device, a chamber, a timing reservoir, valve means having a signaling position for effecting operation of said signal device and for controlling the supply of fluid under pressure to said chamber at a restricted rate 10 and for venting fluid under pressure from said reservoir, and having a normal position for preventing operation of said signal device and for releasing fluid under pressure from said chamber to said timing reservoir, means for effecting the 15 initial movement of said valve means to the signaling position, a valve device operative upon a predetermined increase in the pressure of fluid in said chamber to effect movement of said valve means to the normal position, a repeater valve device 20 operative upon a predetermined increase in the pressure of fluid in said timing reservoir to completely vent fluid under pressure from said chamber and to effect movement of said valve means to the signaling position, another chamber 25 in which the pressure of fluid is adapted to be varied in the signaling position of said valve means, and fluid pressure controlled means operative upon a predetermined variation in fluid pressure in the last mentioned chamber and upon 30 movement of said valve means to the normal position for releasing fluid under pressure from said timing reservoir to prevent further operation of said repeater valve device.

15. In combination, a signal device, a chamber, 35 valve means having a signaling position for effecting operation of said signal device and for controlling the supply of fluid under pressure to said chamber through a restricted passage and having a normal position for preventing operation 40 of said signal device and for releasing fluid under pressure from said chamber, means for effecting the initial movement of said valve means to said signaling position, a valve device operative upon a predetermined increase in the pressure of fluid in said chamber to effect movement 45 of said valve means from the signaling position to the normal position, repeater means operative automatically a predetermined period of time after movement of said valve means to normal 50 position to effect movement thereof to signaling position, flow control means adapted to be connected in parallel with said restricted passage for increasing the rate of supply of fluid under pressure to said chamber, a timing reservoir adapted 55 to be charged with fluid under pressure at a restricted rate when said valve means is in signaling position, means operative upon obtaining a predetermined pressure in said timing reservoir and upon subsequent movement of said valve 60 means to signaling position to render said flow control means effective, and means operative a predetermined period of time after the operation of said valve means is initiated to prevent further operation of said repeater means.

65 16. In combination, a signal device, a chamber, a timing reservoir, valve means having a signaling position for effecting operation of said signal device for controlling the supply of fluid under pressure to said chamber at a restricted rate and 70 for venting fluid under pressure from said reservoir, and having a normal position for preventing operation of said signal device and for releasing fluid under pressure from said chamber to said timing reservoir, means for effecting the initial 75 movement of said valve means to the signaling

position, a valve device operative upon a predetermined increase in the pressure of fluid in said chamber to effect movement of said valve means to the normal position, a repeater valve device operative upon a predetermined increase in the pressure of fluid in said timing reservoir to completely vent the fluid under pressure from said chamber and to effect movement of said valve means to the signaling position, flow control means adapted to increase the rate of supply of fluid under pressure to said chamber, a timing chamber adapted to be charged with fluid under pressure at a restricted rate when said valve means is in signaling position, means operative upon obtaining a predetermined pressure in said timing chamber and upon subsequent movement of said valve means to signaling position to render said flow control means effective, and means operative upon obtaining a predetermined higher pressure in said timing chamber for venting fluid under pressure from said timing reservoir to prevent further operation of said repeater valve device and for opening said chambers to the atmosphere to release fluid under pressure therefrom, the last mentioned means being controlled by the means for effecting the initial movement of said valve means to the signaling position and being operative upon the operation thereof to close communication from said chambers and reservoir to the atmosphere.

30 17. In combination, a signal device, valve means operative upon a reduction in fluid pressure to effect the operation of said signal device, means for initially effecting a reduction in fluid pressure on said valve means, a timing chamber, a valve device operative upon a predetermined increase in fluid pressure in said chamber for controlling the supply of fluid under pressure to said valve means for effecting movement thereof to its normal position for stopping operation of said signal device, and means operative upon movement of said valve means to its signaling position for controlling the supply of fluid under pressure to said chamber at a predetermined rate.

45 18. In combination, a signal device, valve means operative upon a reduction in fluid pressure to effect the operation of said signal device, means for initially effecting a reduction in fluid pressure on said valve means, a timing chamber, a valve device operative upon a predetermined increase in fluid pressure in said chamber for controlling the supply of fluid under pressure to said valve means for effecting movement thereof to its normal position for stopping operation of said signal device, means operative upon movement of said valve means to its signaling position for controlling the supply of fluid under pressure to said chamber at a predetermined rate, and means operative upon movement of said valve means to its normal position for venting fluid under pressure from said chamber.

65 19. In combination, a signal device, valve means operative upon a reduction in fluid pressure to effect the operation of said signal device, means for initially effecting a reduction in fluid pressure on said valve means, a timing chamber, a valve device operative upon a predetermined increase in fluid pressure in said chamber for controlling the supply of fluid under pressure to said valve means for effecting movement thereof to its normal position for stopping operation of said signal device, a timing reservoir, means operative upon a predetermined increase in fluid pressure in said reservoir for effecting a reduction in fluid pressure on said valve means, means operative upon 70

movement of said valve means to its signaling position for controlling the supply of fluid under pressure to said chamber and for venting fluid under pressure from said reservoir, and means operative upon movement of said valve means to the normal position for controlling the supply of fluid under pressure to said reservoir and for venting fluid under pressure from said chamber.

20. In combination, a signal device, valve means operative upon a reduction in fluid pressure to effect the operation of said signal device, means for initially effecting a reduction in fluid pressure on said valve means, a timing chamber, a valve device operative upon a predetermined increase in fluid pressure in said chamber for controlling the supply of fluid under pressure to said valve means for effecting movement thereof to its normal position for stopping operation of said signal device, a timing reservoir, means operative upon a predetermined increase in fluid pressure in said reservoir for effecting a reduction in fluid pressure in said valve means, and for venting the fluid under pressure from said chamber, means operative upon movement of said valve means to its signaling position for controlling the supply of fluid under pressure to said chamber at a predetermined rate, and means operative upon movement of said valve means to its normal position for controlling the supply of fluid under pressure to said timing reservoir at a predetermined rate.

21. In combination, a signal device, valve means movable upon a reduction in fluid pressure to a signaling position to effect operation of said signal device and upon an increase in fluid pressure to a normal position for preventing operation of said signal device, means for initially effecting a reduction in fluid pressure on said valve means, a timing chamber, means operative upon a predetermined increase in fluid pressure in said chamber to effect an increase in fluid pressure on said valve means, a timing reservoir, means operative upon a predetermined increase in fluid pressure in said reservoir to effect a reduction in fluid pressure on said valve means, means operative upon movement of said valve means to a normal position for preventing the supply of fluid under pressure to said timing chamber at a predetermined rate and to vent said reservoir, means operative upon movement of said valve means to normal position for controlling the supply of fluid under pressure to said reservoir at a predetermined rate and to effect venting of fluid under pressure from said chamber, a timing volume, and a valve device operative upon a predetermined increase in fluid pressure in said timing volume to vent said timing reservoir to the atmosphere upon movement of said valve means to the normal position, and means operative in the signaling position of said valve means for controlling the supply of fluid under pressure to said timing volume at a predetermined rate.

22. In combination, a signal device, valve means movable upon a reduction in fluid pressure to a signaling position to effect operation of said signal device and upon an increase in fluid pressure to a normal position for preventing operation of said signal device, means for initially effecting a reduction in fluid pressure on said valve means, a timing chamber, means operative upon a predetermined increase in fluid pressure in said chamber to effect an increase in fluid pressure on said valve means, a timing reservoir, means operative upon a predetermined increase in fluid pressure in said reservoir to effect a reduction in fluid pressure on said valve means, means operative

upon movement of said valve means to signaling position for controlling the supply of fluid under pressure to said timing chamber at a predetermined rate and to vent said reservoir, means operative upon movement of said valve means to normal position for controlling the supply of fluid under pressure to said reservoir at a predetermined rate and to effect venting of fluid under pressure from said chamber, a timing volume, means operative in the signaling position of said valve means for controlling the supply of fluid under pressure to said timing volume at a predetermined rate, a valve device controlling a communication through which fluid under pressure is adapted to be supplied to said timing chamber upon movement of said valve means to the signaling position, for charging said chamber at a faster rate, and operative upon a predetermined increase in fluid pressure in said timing volume to open said communication, and a valve device operative upon a predetermined greater increase in fluid pressure in said timing volume and upon subsequent movement of said valve means to normal position for venting said timing reservoir to prevent further operation of the means controlled thereby.

23. In combination, a source of fluid under pressure, a device comprising a casing having a chamber and containing a movable abutment subject on one face to the pressure of fluid in said source and on the opposite face to the pressure of fluid in said chamber, said casing having a relatively restricted feed passage and also a normally open passage having relatively large flow capacity, both of said passages connecting said source to said chamber and adapted to supply fluid under pressure to said chamber at such a rate as to prevent a differential of fluid pressures exceeding a predetermined degree of developing on said abutment during charging of said chamber, a valve controlling communication through said normally open passage, means for seating said valve to close said communication, a spring, and a movable abutment subject to the opposing pressures of fluid in said communication and said spring normally holding said valve unseated and operative to permit seating of said valve when the pressure of fluid obtained in said communication becomes sufficient to overcome that of said spring.

24. In combination, means having a normal position and having a position for effecting a signal, a device operative to effect an initial movement of said means from said normal position to the signaling position, mechanism controlled by said means and set in operation upon an initial movement of said means to signaling position for automatically effecting alternate movements of said means first to the normal position and then to the signaling position, and means controlled by the first named means operative automatically to stop said first named means in normal position after said first named means has been automatically moved to the signaling position a predetermined number of times.

25. In combination, means having a normal position and having a position for effecting a signal and operative upon a series of successive alternate movements from one position to the other to effect a series of successive signals, a device operative to effect the initial movement of said means to the signaling position, mechanism set in operation by said means upon the initial movement thereof to signaling position for automatically effecting said successive alter-

nate movements of said means, and means set in operation upon initiating the operation of the first named means and operative at the termination of a predetermined number of said successive movements to prevent movement of said first named means out of normal position.

26. In combination, means having a normal position and having a position for effecting a signal, a device operative to effect the initial movement of said means from said normal position to the signaling position, mechanism controlled by said means and set in operation upon the initial movement of said means to the signaling position for automatically effecting movement thereof to the normal position after a predetermined period of time in said signaling position and automatically operative a predetermined period of time after movement of said means to normal position to again effect movement thereof to signaling position, means for again returning said first named means from signaling to normal position, and means controlled by the first named means and operative automatically a predetermined period of time after the initial movement of the first named means to the signaling position to hold said first named means in normal position.

27. In combination, means having a normal position and having a position for effecting a signal, a device operative to effect the initial movement of said means from said normal position to the signaling position, mechanism controlled by said means and set in operation upon the initial movement of said means to the signaling position for automatically effecting movement thereof to the normal position after a predetermined period of time in said signaling position and automatically operative a predetermined period of time after movement of said means to normal position to again effect movement thereof to signaling position, means for again returning said first named means from signaling to normal position, and means controlled by the first named means and operative automatically a predetermined period of time after the initial movement of the first named means to the signaling position to render said mechanism ineffective to effect movement of the first named means out of normal position.

50 28. In combination, means having a normal position and movable therefrom to a signaling

position for effecting a signal indication, a device having a certain position and movable therefrom to effect movement of said means from normal position to signaling position, said device being then movable back to said certain position, and mechanism controlled by said means and operative automatically after the initial movement of said means to signaling position and with said device in said certain position to effect alternate movements of said means first to normal position and then back to signaling position, and means operative automatically to stop the first named means in normal position at the termination of a predetermined series of said alternate movements.

29. In combination, means operative upon a decrease in fluid pressure to effect a signal and upon an increase in fluid pressure to cease signaling, a device having a normal position and movable to another position for effecting a reduction in fluid pressure on said means and then movable back to said normal position, mechanism operative automatically after movement of said device back to normal position to effect a series of successive increases and decreases in fluid pressure on said means, and means operative automatically after the fluid pressure on the first named means has been decreased a predetermined number of times to prevent further operation of said mechanism to reduce the fluid pressure on said means.

30. In combination, means operative upon a decrease in fluid pressure to effect a signal and upon an increase in fluid pressure to cease signaling, a device having a normal position and movable to another position for effecting a reduction in fluid pressure on said means and then movable back to said normal position, mechanism operative automatically after movement of said device back to normal position to effect a series of successive increases and decreases in fluid pressure on said means, and means operative automatically after the fluid pressure on the first named means has been decreased a predetermined number of times to prevent further operation of said mechanism to reduce the fluid pressure on said means, said mechanism and last named means being controlled by the first named means.
